UNITED STATES PATENT OFFICE.

WESTON M. FULTON, OF KNOXVILLE, TENNESSEE, ASSIGNOR TO THE FULTON COMPANY, OF KNOXVILLE, TENNESSEE, A CORPORATION OF MAINE.

RADIATOR.

1,170,625.

Specification of Letters Patent.

Patented Feb. 8, 1916.

Application filed March 2, 1914. Serial No. 821,991.

To all whom it may concern:

Be it known that I, WESTON M. FULTON, a citizen of the United States of America, and a resident of Knoxville, Tennessee, have 5 invented a new and useful Improvement in Radiators, which invention is fully set forth in the following specification.

This invention relates to steam and hot water radiators, and more particularly to radiators of the class designed to be inclosed in a casing through which the air to be heated is caused to circulate by convection.

Steam and hot water radiators heretofore provided with casings for confining the air 10 in contact with the radiator sections while being heated are wasteful of heat and lack compactness. Portions of the air passing through the casing escape without proper contact with the heating surfaces of the coils 15 and other portions remain in contact with the coils longer than is necessary to attain the temperature of the heating medium. The upper portions of the radiator become 20 therefore ineffective and are a source of loss 25 in heating.

It is recognized in this art as advantageous to introduce the steam or hot water at the top of the radiator, and to secure this advantage it is the universal practice to extend the supply pipe alongside the radiator 30 to the top, thereby making it necessary to inclose this pipe in the casing. This requires a larger casing than would be necessary to inclose the radiator itself and is often 35 unsightly.

The object of the present invention is to overcome these objections, and with this object in view the invention, broadly stated, 40 consists in providing a casing within which is placed a radiator (preferably sectional), so arranged in the casing that the air which enters at the bottom of the casing is compelled to pass upwardly between the sections of the radiator, and providing said sections 45 with ribs (either solid or hollow) or other means for directing the course of the air in its upward movement. The number and size of the ribs may vary and they are so shaped and disposed with reference to each other as 50 to afford channels with a minimum retardation of flow. In the form of radiator chosen to illustrate the invention, this result is accomplished by giving to the ribs a general direction corresponding to a compound curve, the under surface of each rib being

concaved next to the receiving or cool air side of the radiator and convex next to the upper or discharge side of the radiator, whereas the upper surface of each rib is convex at the receiving or cool air side of the radiator and concaved at the upper or discharge side thereof. The result of this construction is that channels are provided between the ribs whose upper walls are concaved and whose lower walls are convex at the receiving or cool air side of the radiator while its upper walls are convex and its lower walls are concaved at the discharge or hot air side of the radiator. The surfaces of these ribs may assume various double or compound curve forms, but the form which has given the best results is constructed on the lines of a double cycloidal curve or approximately such a curve and is the one which I prefer. Ribs constructed on this curve afford the 75 quickest possible passage for the air deflected through the channels formed between them.

Preferably, the radiator is inclined within the casing and thus forms a channeled partition, through the channels of which all the air is forced to pass on its way from the bottom to the top of the casing. Preferably also the radiator forms with the wall of the casing on the delivery side of the radiator 80 a gradually enlarging chamber which accommodates the expanding volume of air as it is increasingly heated in passing through the channels between the sections and cooperates with the peculiar design of the ribs 85 to facilitate the movement of the air through and from the casing. Furthermore, the radiator forms a chamber gradually decreasing in cross-sectional area from the bottom upward, so that while there is maintained at 90 all times an ample supply of air to pass through the channels between the ribs of the sections of the radiator, nevertheless all of the air that comes in contact with the lower side of the radiator is compelled to pass upwardly through said channels and be discharged into the chamber formed between the casing and the radiator on the upper side of the latter. While this specific arrangement of the radiator with relation to 95 the casing is the one preferred, it is not essential, since the radiator may be arranged in other relations with regard to the casing while still preserving to a greater or less extent the benefits of the invention. The sec- 100 105 110

tions of the radiator may be either of a uniform width from top to bottom or they may be made narrower at the top than at the bottom, as desired, and the casing instead of being formed separately from the radiator may, if desired, be cast in sections integral with the radiator sections and constitute a built-up casing which will inclose the inclined sectional radiator.

10 In order to support the radiator sections in their inclined position, supporting sections are preferably provided, one at each end of the radiator and one or more intermediate the ends when the length of the radiator requires additional support. These supporting sections are preferably triangular in shape and are cast with legs; and to permit greater compactness of the casing, the interior of one of these supporting sections is 15 provided with a vertical passage opening at its top into a steam space forming the heating chamber of the section and preferably connects at its base through a drain passage with said steam space. This avoids the necessity of making the casing large enough to 20 inclose the heat supply pipe. Where separable casings are employed, these supporting sections are also provided with ledges on which the casing is adapted to rest. In the 25 detailed description, the above and other features of the invention will be more fully explained.

In order that the invention may be more readily understood, reference will be had to the accompanying drawings showing some of the mechanical expressions of the inventive idea, but the drawings are intended merely to assist the description and not as defining the limits of the invention.

30 40 In the drawings:—Figure 1 is a view showing in elevation an end supporting section of a radiator constructed in accordance with my invention and the casing therefor in section; Fig. 2 is a horizontal section taken on line 2—2 of Fig. 1; Fig. 3 is a vertical section through a supporting radiator section taken on the line 3—3 of Fig. 2; Fig. 4 is a view showing in elevation an intermediate radiator section provided 45 with cycloidal ribs and a casing in section; Fig. 5 is a view showing in elevation one of the intermediate radiator sections provided with a bracket for supporting the casing shown in vertical section; Fig. 6 is an enlarged detail perspective view showing cycloidal ribs on an intermediate section of the radiator; Fig. 7 is a transverse sectional view taken on the line 7—7 of Fig. 6; Fig. 8 is an elevational view of a 50 radiator section embodying the principles of my invention, showing a sectional casing as an integral portion of the radiator section; Fig. 9 is a transverse sectional view taken on line 9—9 of Fig. 8; Fig. 10 is a rear elevational view with a part of the casing re-

5 moved to show the arrangement of the radiator sections; and Fig. 11 is a view shown in part elevation and part section showing a slight modification of one of the radiator sections.

60 Referring to the drawings, the radiator comprises preferably a plurality of inclined sections 1, the number and size of which may vary to meet the requirements of the space to be heated. In order to maintain the 70 sections in their inclined position, supporting sections 2 are provided which are located at the ends of the radiator and, if additional support is required, one or more of these sections may be located intermediate 75 the ends. In Figs. 1, 3 and 10, such supporting sections are illustrated, and each preferably comprises a hollow casting triangular in shape having a base 3 provided with legs 4 and ledges 5 on which a casing 6 may rest. In the vertical side of the supporting section, a steam or hot water supply passage 7 is provided, which opens through a duct 8 into the top of the heating chamber 9 of the section. Bosses 10, 11 and 12 80 are tapped into each side wall of the section for the introduction and discharge of the heating medium and for connecting with other sections of the radiator. A drain passage 13 is also preferably provided between 85 chamber 9 and supply passage 7, and means provided for closing it, such as screw plug 14, which may be inserted through an opening 15 in the wall of the casting, which latter is adapted to be closed by similar means. 90 It is preferable to make all the supporting sections alike to give them interchangeability, but where these sections are to be used as end sections, only the boss 11 need be provided in the end face of the section for connecting with a supply pipe 16, and two bosses 10, 12 provided on the opposite side for connecting with the next section. If, however, the full complement of openings 95 is provided in these sections, those not to be 100 used are closed by plugs.

105 Intermediate the end supporting sections 2, 2, I locate the inclined sections 1, one of which is shown in Fig. 4 and a description thereof will serve for the other like sections. Section 1, as illustrated, has an elongated rectangular cross section and consists of a casting provided with suitable bosses at the top and bottom, and on opposite sides, for connecting with its companion sections 110 which are spaced apart to permit passage of air between the sections. The opposite side walls of the section 1 are provided with a plurality of ribs 17 of my improved design. These ribs may be solid or hollow 115 and, in either case, each rib presents on its downwardly facing side a surface having a concaved portion running into a convex portion, with the concave surface located next to the cool air side of the radiator section and 120 130

the convex portion located at the outgoing or heated air side of the radiator section. The rib on its upwardly facing side presents a similar double curve, the positions of the 5 concave and convex portions being reversed with relation to the two sides of the radiator section. While I do not wish to be limited to any particular form of double curve, I prefer to give these surfaces a 10 double cycloidal curve, since I find this curve facilitates the flow of air past the sections while it is deflected by the ribs. These ribs are arranged in a parallel relation with each other across the faces of each section, 15 their general direction approaching the vertical in the normally inclined position of the radiator section. The ribs 17 on adjacent sections are so positioned and are of such a height that they meet to form passages 20 conducting the air across the sections from the air intake side to the discharge side. The length of the passages may vary to meet different conditions of heating, but should be of such length that the air leaving the 25 sections approximates the temperature of the heating medium and not long enough to present idle heating surface after the air reaches this temperature. In Fig. 6, I have shown in enlarged view two of the ribs 17 30 as they appear on the face of a section 1, and in Fig. 7 a cross-sectional view of two hollow ribs 17 one in each side of the section.

The assembled sections, including the 35 supporting sections 2 and intermediate inclined sections 1, are inclosed by a casing 6 which may be of any approved form. The casing illustrated is provided with a hood 18 and houses dampers and damper-operating means. This casing is placed over the 40 radiator and is supported on ledges 5, 5 formed on the bases 4 of the end sections. The radiator thus forms an inclined partition located diagonally between the upright 45 walls of the casing and between the inlet or bottom opening of the casing and the top outlet which, as shown, is formed in the hood 18 and is located at the front of the radiator. Two chambers are thus formed, 50 one between the lower side of the radiator and the casing wall, and the other chamber between the upper side of the radiator and the opposite casing wall. The first-named chamber constitutes a receiving chamber for 55 air entering the base and from which it is discharged through the above-described passages between the heating sections into the second chamber. It is to be here noted that the air on arriving at the entrances of 60 the passages is deflected by the downwardly facing concaved surfaces of the ribs without giving a sharp change of direction, and is again deflected in a like manner while being accelerated in velocity by expansion 65 when it reaches the delivery ends of the

passages. The air has thus been caused to cross the heating sections and its course has been deflected to secure the necessary duration of contact for maximum absorption of heat, while avoiding the resistance of sharp 70 bends to flow of air currents and the unnecessary duration of contact of the air with the heating surfaces; and to further facilitate the flow of air heated and expanded by the hot surfaces of the radiator passages, the 75 delivery chamber gradually increases in size to accommodate the increased volume.

In order to enlarge the delivery chamber without increasing the size of the casing, I 80 may make the radiator sections narrower at the top than at the bottom, as shown in radiator section 1' Fig. 11, other features of the construction remaining the same.

In radiators made up of many sections, it may be desirable to provide additional 85 support for the casing, and for this purpose I preferably provide one or more of the intermediate sections with a bracket arm 19 having a shoulder 20 in line with shoulders 5 of the end sections. Such construction is 90 shown in Fig. 5.

Instead of making the casing separable, I 95 may make it integral with the inclined radiator, in which case each intermediate section is provided with plates 21 adapted to be supported by arms 22 projecting from 100 the sections. The edges of the plates are provided with shoulders 23 permitting them to be matched to each other to form a closed joint when the sections are 100 assembled as shown in Figs. 8 and 9. If desired, these plates may be extended above the radiator to form a hood for housing the damper-operating means.

What is claimed is:

1. In combination, a vertical radiator casing through which air to be heated passes, a sectional radiator in said casing constituting a partition between the inlet and outlet ends of said casing, opposing 105 ribs on adjacent sections constituting top and bottom walls of passages through which air to be heated passes, said walls having double cycloidal outline for facilitating flow of heated air through said passages.

2. In combination, a radiator casing through which air to be heated passes, a radiator in said casing extending diagonally between its vertical walls and located between the inlet and outlet ends of said casing and having passages through which air to be heated passes on its way through the casing, said passages having top and bottom walls approximately cycloidal in outline.

3. In combination, a vertical radiator casing through which air to be heated passes, a radiator in said casing adapted to extend diagonally between the vertical walls of said casing and forming with the casing on 130

its delivery side a chamber progressively increasing in size toward the outlet end of the casing, said radiator being provided with passages through which air to be heated passes, said passages having top and bottom walls cycloidal in outline for facilitating the flow of said heated air.

4. In a radiator having sections normally inclined from the vertical, an end section 10 adapted to be associated therewith comprising a casting for supporting the associated sections in their inclined position and having a chamber open to said sections, and a vertical passage within said end section for supplying heating fluid to the top of said chamber.

5. In a radiator having sections normally inclined from the vertical, an end section 20 adapted to be associated therewith comprising a casting for supporting the associated sections in their inclined position and having a chamber open to said sections and a vertical passage within said end section open at the top to said chamber for supplying heating fluid thereto, and a drain passage between said chamber and supply passage and means for opening and closing the same.

6. An inclosed radiator having sections 30 normally inclined to the vertical, ribs on adjacent sections forming top and bottom walls of passages through which air to be heated passes, said walls having the outline of double cycloidal curves for facilitating the flow of said heated air.

7. A radiator having sections normally inclined to the vertical, ribs on adjacent sections forming top and bottom walls of passages through which air to be heated passes, 40 said walls having the outline of double cycloidal curves for facilitating the flow of said heated air.

8. In combination, a radiator casing through which air to be heated passes, a 45 sectional radiator in said casing constitut-

ing a partition between the inlet and outlet ends of said casing and having passages between them through which air to be heated passes on its way through the casing, the passages at the top of the radiator being shorter than those at the bottom, for the purpose described.

9. In a radiator having sections, an end section consisting of a casting for supporting the associated sections and having a 55 chamber open to said sections and a vertical supply passage within said end section open at the top to said chamber for supplying heating fluid thereto, and a drain passage between said chamber and supply passage, and means for opening and closing the same.

10. In combination, a radiator casing through which air to be heated passes, a sectional radiator in said casing constituting a partition between the inlet and outlet ends of said casing, the sections being narrower at the top than at the bottom and having opposing ribs constituting top and bottom walls of air passages, said walls 70 having double cycloidal outline for facilitating flow of heated air through said passages.

11. In combination, a vertical radiator casing through which air to be heated 75 passes, a radiator in said casing adapted to extend diagonally between the vertical walls of said casing and located between the inlet and outlet ends of said casing and provided with passages having top and bottom walls 80 conforming in outline to double cycloidal curves whose rectangular axes lie in vertical and horizontal planes.

In testimony whereof I have signed this specification in the presence of two subscribing witnesses.

WESTON M. FULTON.
